ABSTRACT OF THE DISCLOSURE

This invention relates to a new and improved portable air-conditioning unit. The structural elements of the unit include an enclosure which provides an air inlet, and air outlets. A condenser and evaporator, respectively, lie within the air flow paths through the outlets. A compressor and fan can be energized via virtually any convenient source of power to transfer heat to and from and blow air across both the condenser and evaporator. An adjustably mounted baffle or vane is preferably used to regulate the flow of air from the fan, causing it to flow over the condenser and evaporator in optimum proportions.

In certain environments, particularly during the extreme cold of winter or the extreme heat of summer, there is need for air conditioning. In the heat of summer, e.g., the interiors of certain vehicles, e.g., airplanes, boats, trailers and the like, become uncomfortably hot. In certain situations this condition persists even when the vehicle is properly equipped with an air-conditioning system. Thus, e.g., until the plane is airborne its relatively complex air conditioning, or primary, unit cannot function until its engines are generating sufficient power. This means in most instances, of course, that passengers must endure the interim discomfort.

Often, also, it is necessary that work be performed in uncomfortably warm or cold spaces or zones. Because of the urgency of the situation, the work cannot often be delayed. Sometimes, e.g., workers or repair men must spend several hours or days in a tunnel or manhole below a street. The discomfort and unpleasantness of the situation must be borne because of the impracticality of providing a more or less permanent air-conditioning installation.

In view of these and other difficulties, and because of the need for fresh air in these and other situations, it is an object of the present invention to advance the state of the art by providing a new and improved portable air-conditioning unit. In particular, it is an object to provide a highly durable and efficient unit of relatively simple construction for independently mounting and ease of transport to a location for use in conditioning a space or zone by warming or cooling. More particularly, it is an object to provide a portable air-conditioning unit admirably suitable for providing warm or cold air in large volumes on short demand.

These and other objects are achieved in accordance with the present invention which comprises, in a combination: an enclosure or casing which contains air inlet and air outlets, a condenser and an evaporator each located within or adjacent to an air outlet. The condenser and evaporator are connected through a compressor for circulating refrigerant to effect proper heat exchange. A single fan draws air from the inlet and blows it over the condenser and evaporator. Both the fan and the compressor are powered by the same source.

A pivotally mounted baffle or vane is preferably used to regulate or proportion the flow of air from the fan across the condenser and evaporator, and through the respective outlets.

A key and novel feature of the invention resides in its

2

extreme simplicity. The number of component parts has been reduced to an absolute minimum. A single fan draws air from an inlet into the enclosing housing, the air contacting the condenser and evaporator upon passing through the outlets. The flow can be proportioned by regulating the resistance provided by a respective outlet as by sizing the outlets. A particularly preferred combination is one which includes a single fan and proportioning vane by virtue of which air from the fan can be readily regulated to flow across both condenser and evaporator, and through the outlets, in the desired proportions, such installation including both fan and compressor mounted in the same train, and driven by the same power source.

15 The invention will be better understood by reference to the following detailed description and to the attached drawings to which reference is made in the description.

In the figures:

FIGURE 1 is a side elevation view of a preferred embodiment.

20 FIGURE 2 is a plan view taken along section 2—2 of the preceding figure, these figures showing the combination of a single fan and compressor mounted on the same shaft, and driven by the same power source; including also the combination of a single fan and proportioning vane for regulating and proportioning the flow of intake air across both the condenser and evaporator.

25 FIGURE 3 is a fragmentary plan view depicting a structure for proportioning intake air across both the condenser and evaporator without use of a proportioning vane.

30 FIGURE 4 is a front elevation view taken along section 4—4 of FIGURE 3.

35 FIGURE 5 is a fragmentary view of a sub-assembly for positioning the vane, the view being taken along section 5—5 of FIGURE 1.

40 FIGURE 6 is a diagrammatic view showing the internals of the condenser and evaporator in relationship to the compressor, fan and power source.

45 Referring to FIGURE 1 is shown a housing or casing 10 provided with an air inlet 11 and air outlets 12, 13. The housing is formed into two compartments by the partitioning wall 8 provided with a central opening 9. The air inlet 11 (or a plurality thereof), shown positioned at the rear of the casing 10, if desired, can be located in the forward portion of the rear compartment; or even in the forward compartment, as will be subsequently discussed. A condenser 14 and evaporator 15 are located within air outlets, 12, 13, respectively, of the forward compartment.

50 A fan 16, extending into the opening 9, and gasoline motor 17 are mounted on a common shaft 18, which is coupled or geared to a compressor 7. Exhaust gas is vented from motor 17 via escape through the exhaust tube 17. The source of power can be an electric motor, gasoline motor, steam engine, steam turbine, or the like.

55 Preferably, a vane or baffle 4 is provided to regulate and proportion the flow of air through the forward compartment. The vane 4 is pivotally connected, or hinged via a hinge 5, to the upper and lower walls of casing 10 and located between outlets 12, 13. The vane 4 can be pivotally moved either to the left or right via movement of the arm 3 (FIGURE 5) riding within the slot 1 to proportion and regulate the flow of air from fan 16 across the condenser 14 and evaporator 15. Thus, warm air and cool air, respectively, can be conveyed through the outlets 12, 13. Where, e.g., it is desired to deliver cold air through outlet 13, the optimum cooling is determined by positioning the vane 4 and, when determined, the position of the vane is set by tightening down set screw 2.

60 In cooling a vehicle, e.g., the unit can be conveniently

ounted and transported on a dolly (not shown), connected up with a convenient power source, and cold air can be delivered via a conduit connected between the outlet 13 and the space or zone to be cooled. Only ambient air is pulled into the unit via inlet 11, and there is no recycle of air from the space or zone being cooled.

Referring to FIGURE 3 there is shown the forward section of an air conditioning unit using a different principle or proportioning air between a condenser and evaporator. In this embodiment, a fan 26 is mounted within an air intake opening 29 located within a forward compartment of a casing 20 divided by a partitioning wall 08. The fan 26, mounted on a shaft 28 and operatively connected through a coupling 06 to a gasoline motor 27, draws air into the compartment and distributes it between the condenser 24 and evaporator 25 as determined by the frictional resistance offered by the predetermined size of the openings 22, 23. In this embodiment there is no warming of the intake air as by contact with a hot motor or compressor which, where cold air is the important factor, provides some advantage in increased efficiencies. Thus, there is no need to shield these elements or to reposition the inlet 11 (FIGURES 1 and 2) upstream of these elements where increased efficiency is desired.

Referring to FIGURE 6 is shown a diagrammatic view illustrating the relationship between the compressor and the condenser and evaporator. A line 14¹ thus contains a suitable coil 14, constituting the heat exchange element of the condenser, and a line 15¹ contains a suitable coil 15, constituting the heat exchange element of the evaporator. Lines 14¹ and 15¹, each of which connects directly to the compressor 7, are coupled together through a constant pressure regulator. A drier 04 is generally provided. Refrigerant is compressed or condensed within coil 14 to liberate heat, and is expanded or evaporated under reduced pressure within coil 15 to absorb heat. Air is warmed or cooled, respectively, by passage over the coils. The clutch 6 provides a means whereby the unit can be operated without heating or cooling the intake air. This is useful when this ambient air being taken in, and blown out through either coil, is at the proper temperature, without modification.

A transition duct or fixture and attached flexible hose shown in FIGURE 3 in broken lines) is positioned at outlet 13 to convey or transport the cooled air from coil 15 or at outlet 12 to convey or transport the heated air from coil 14 to any desired location.

It is apparent that various modifications and changes can be made without departing from the spirit and scope of the invention.

Having described the invention, what is claimed is:

1. In a portable air-conditioning unit, the combination comprising:

- 5 a casing provided with air inlet and air outlets, a condenser and an evaporator, each located at an air outlet,
- 10 a compressor for circulating a refrigerant via appropriate lines between the condenser and evaporator, a single fan for drawing air into the casing, means for regulating and proportioning the intake air from the fan across the condenser and evaporator, and through the outlets,
- 15 a single drive train on which both the compressor and fan are operated,
- 20 a single power source for driving the compressor and fan.
2. The apparatus of claim 1 wherein the casing is divided into two compartments by a partitioning wall containing an opening, the air inlet compressor and power source are located within one compartment, and the fan is located at the opening to provide intake air to the adjacent compartment which contains the condenser and evaporator.
3. The apparatus of claim 2 wherein the air inlet is located to the rear of the compartment containing the compressor and power source.
4. The apparatus of claim 2 wherein a movable vane is provided in the adjacent compartment between the condenser and evaporator to regulate and proportion the amount of air flowing over these respective members.
5. The apparatus of claim 4 wherein the movable vane is provided with a connecting arm external to the casing, action upon which causes movement of the vane.
6. The apparatus of claim 1 wherein the casing is divided into two compartments by a partitioning wall, the compressor and power source are located within one compartment, the fan is located within an air intake opening in the adjacent compartment, and the outlets are sized to regulate and proportion the amount of air flowing over the condenser and evaporator.
7. The apparatus of claim 1 wherein an outlet is provided with a transition duct and flexible hose for conveying the conditioned air to a desired location.
